UNITED STATES PATENT OFFICE

CHAUNCEY ARNOLD DUTTON, OF SHAKER HEIGHTS VILLAGE, OHIO, ASSIGNOR TO
FERRO ENAMEL CORPORATION, OF CLEVELAND, OHIO, A CORPORATION OF OHIO

ENAMELING FURNACE

Application filed December 3, 1930. Serial No. 499,724.

My invention relates to furnaces, and more particularly to a furnace which is adapted for such use as burning enamel; although it might well be used for heat treating, annealing, or soaking metals; in which high temperatures are used.

It is among the objects of my invention to provide a furnace through which such articles as enamel ware are continually moved; 10 wherein the burning chamber is vertically disposed having one opening through which uninterrupted streams of incoming and outgoing ware may pass; wherein the furnace also comprises a horizontally disposed pre- 15 heating and cooling chamber adjacent the burning chamber wherein the burned and unburned ware passes in vertically disposed streams so that the burned ware in passing under the unburned ware delivers heat there- 20 to.

Other objects contemplate the provision of a furnace being economical of construction, having a low maintenance cost and greater firing efficiency in an equivalent production 25 of ware; a furnace in which all of the moving parts with the exception of the chain and its attachment with tools and ware are kept out of the high heat zone; including a pawl and ratchet mechanism for securing the shafts 30 against movement in the upper part of the furnace in case the ware carrying apparatus should break; and further the provision of a furnace which will be easily accessible to remove any pieces of ware which might fall 35 from the conveyor.

A still further object is to provide an offset construction in the ware carrying mechanism which will permit the ware to be continuously supported within the high heat zone while 40 the conveyor chain is adapted to pass out of the heating chamber.

Other objects will appear from the following description of the preferred form of my invention, with reference to the accompanying drawings wherein similar characters of reference designate corresponding parts and wherein:—

Figure 1 is a diagrammatical view of the assembled enameling furnace and preheating 50 and cooling chamber;

Figure 2 is a vertical sectional view illustrating the preferred embodiment of my enameling furnace;

Figure 3 is a side elevation of the furnace;

Figure 4 is a plan view of the burning 55 chamber;

Figure 5 is a fragmentary view taken on a plane through the line 5—5 of Figure 4;

Figure 6 is a fragmentary view partly in section of the stub shaft and sprocket disposed 60 in the base of the heating chamber;

Figure 7 is a plan view of the driving mechanism for the conveying apparatus;

Figure 8 is a side elevation of the driving mechanism and the end sprockets at the outer 65 end of the preheating chamber;

Figure 9 is a side elevation of a section of the conveyor apparatus;

Figure 10 is a view taken on a plane through the line 9—9 of Figure 8. 70

With reference to the drawings I have shown diagrammatically in Figure 1 an enameling furnace 1 as comprising a vertical burning chamber 2, which may be constructed of any suitable material such as fire brick 75 or the like, a horizontal preheating and cooling chamber 3, and a conveyor mechanism 4, although I do not wish to be limited to the embodiment herein illustrated.

With reference to Figures 2 and 3 I have 80 illustrated the preferred embodiment of my burning chamber as comprising a base 5 having a port 6 large enough to receive the ware and proper conveyor mechanism which hereinafter will be referred to more in detail. Opposite the port 6 is disposed an opening 7, provided with a door 8 to make the burning chamber easily accessible whereby any ware dropped from the conveying apparatus might be removed during the enameling operation. 85

An arch 9 is disposed across the opening 10 in the top of the base 5 to retard any flow of heat downwardly from the radiant heat zone of the furnace. Disposed on the base 5 is a cylindrical burning chamber or muffle 11 of the full muffle type having a top 12 thereon. The muffle is preferably divided into halves each with three horizontal passes 13, 14 and 15, in which fuel is fired to the bottom pass 13 through the burners 16 and 17 on 95 100

opposite sides of the furnace. The products of combustion pass horizontally through the pass 13, back through the pass 14, then in an opposite direction through the pass 15 and 5 out through suitable exhaust ports 18 and 19 on the opposite sides of the furnace. The use of a split muffle facilitates a greater heat control within the burning chamber in that it is possible to increase the heat in the section 10 facing the cool ware. Where it is necessary to obtain a still greater control of the heat within the heating chamber, I contemplate the use of a plurality of burners, for example, a burner feeding into each one of the 15 passes 13, 14 and 15 on opposite sides of the furnace.

A dead wall space 20 is provided between the top of the muffle 11 and the top 12 of the furnace. This dead wall space is provided in 20 order that the upper portion of the ware will be carried partly out of the radiant heat zone, on its travel therethrough, to permit the lower portion of the ware to be equal or possibly at a slightly higher temperature than the 25 top portions of the ware before the return trip downwardly through the burning chamber. While I have illustrated a furnace operable with fluid or gaseous fuel, it is to be understood that the precepts of my invention are 30 broad enough to include various kinds of heating mediums combustible or otherwise, especially the use of electrical elements. It might be further noted that the flow of gas through the muffle might be reversed, the 35 burners projecting into the pass 15 and the exhaust ports communicating with the pass 13.

As is shown in Figure 1 a preheating and 40 cooling chamber 3 may extend outwardly horizontally from the base 5 of the burning chamber 2 and communicates therewith through the port 6. The chamber 3 as shown is of a rectangular configuration having an outwardly extending canopy 21 which may 45 extend over the entire conveyor mechanism, the ware loaded thereon as at 22. Baffle plates 23 and 24 extending upwardly from the bottom and downwardly from the ceiling of the chamber, respectively, are disposed throughout the length of the chamber. The provision of the baffles is to retard the 50 flow of heat from the heating chamber and to interrupt and retard the tendency of any air to circulate into and out of the furnace. There are two sets of trackways 25 and 26 55 each having one section thereof secured to the opposing walls of the preheating chamber. These trackways 25 and 26 are adapted to provide slide supports for the chain carrying 60 the unburned and burned ware, respectively, in its travel through the preheating and cooling chamber.

The conveying mechanism 3 (Figures 2 and 3) is comprised of two parallel chains 27 65 and 28 which are properly guided through

the preheating and burning chambers 3 by sprockets, rollers or curved shoes, as might be desired, disposed on the inner ends of stub shafts which will be referred to, hereinafter, more in detail. The parallel chains 27 and 70 28 are adapted to have inwardly protruding pins or lugs 29 thereon (Figures 9 and 10) which pivotally support rods 30 which project downwardly and are free moving in a vertical plane. The rods 30 are parallel and 75 opposite each other on the two chains. The length of the rods 30 depends upon the size of the supporting sprocket 31 at the top of the roof 12, the thickness of the roof 12 of the heating chamber, and the size of the ware 80 to be conveyed. The depending ends of the oppositely disposed rods 30 have secured thereto a suitable burning tool 32 which supports the ware as it is conveyed through the furnace.

The ware is loaded on the tools 32 as at 22 under the hood 21, the conveyor chains 27 and 28 travel away from the furnace proper (Figure 1) up over the sprockets 33 which have attached thereto a suitable driving mechanism 33' as is shown in Figures 7 and 8, and back horizontally through the preheating chamber 3. At the end of the preheater, the chains turn upwardly over sprockets 34 which are secured to stub shafts 35, journaled in suitable bearings 36 which might be cooled by water or other means, and in turn are supported in recesses or ports 37 disposed in the walls of the base 5 of the burning chamber; (Figure 3) and upon further travel enter the burning zone 38 of the furnace. The chains upon reaching the upper zone of the burning chamber continue through slots 39 in the top 12 of the burning chamber and travel over hooded sprockets 31 which are secured on the inner ends of stub shafts 40 (Figures 4 and 5) mounted above the upper surface of the roof 12 of the furnace. The shafts 40 are journaled in suitably cooled bearings 41 supported in brackets 42. The brackets 42 are adapted to raise or lower the shafts 31 in order that the tension on the conveyor mechanism 4 may be varied accordingly as different size or weight of ware is conveyed through the furnace or as the temperature of the furnace expands the chain elements. The size of the sprockets 31 at the top of the furnace determines the width of the ware or tooling the furnace will accommodate. If the ware is too large it is possible to have two or more sets of sprockets at the top of the furnace to prevent the downwardly moving ware from colliding with the upwardly moving ware. The use of the 110 hoods 43 is to prevent any loss of heat through the slots 39, although other means such as air screens might be used in the place of the hoods.

As the chain travels out of the top of the 115 furnace the ends of the rods attached to the 120

chain move with the chain out of the furnace (Figure 2), but the end carrying the cross bar or turning tool supporting the ware does not leave the hot zone. The advantage of this

5 construction resides in the fact that all of the moving parts except the chain and its attachments with tools are kept out of the high heat zone.

10 After passing over the sprockets 31 at the top of the furnace, the chain travels downwardly through the hot zone and then around the sprockets 44 secured to the stub shafts 45 journaled in suitably cooled bearings 46 supported in the oppositely disposed openings 47 15 in the base 5 of the burning chamber. The sprockets 44 are so disposed with relation to the sprockets 34 that the outgoing ware will not collide with the incoming ware. From the sprockets 44 the outgoing chain is guided 20 parallel to the incoming chain, in the pre-heating chamber, but in an opposite direction, the outgoing chain being disposed beneath the incoming chain. The outgoing ware thus delivers heat to the incoming ware 25 as they pass in opposite directions in the pre-heating chamber. Although this means is an economical one of preheating the unburned ware, auxiliary heating or drying means might be introduced into the preheating 30 chamber or gas could be conveyed from the outlet ports of the muffle to the preheating chamber.

35 A pawl and ratchet construction 48 (Figures 4 and 5) fixed to the upper shafts 40 co-operating with a limit switch (not shown) is operable to stop the driving mechanism, and secure the shaft 40 against movement upon any reverse movement of the sprockets 31 as would be the case if the conveying 40 mechanism should break.

45 Although as disclosed the sprockets 31 are supported on the upper side of the roof plate 12, it is contemplated that the shafts 40 and sprockets 31 might be disposed within the upper limits of the heating chamber as in the zone 20. This provision would obviate the offset conveying rods and would substantially reduce the initial cost of the furnace.

50 Having described certain preferred embodiments and applications of my invention, it is to be understood that I do not limit myself to the forms shown but that a variety of other forms may be used in practice, so long as they fall within the scope delimited 55 by the following claims.

I claim:

1. An enameling furnace comprising a vertical burning chamber, heating means intermediate the ends of said chamber and a horizontal preheating and cooling chamber.

60 2. An enameling furnace comprising a vertical burning chamber, heating means in said chamber, a horizontal preheating and cooling chamber, and conveyor means for carrying 65 ware through the said chambers.

3. A furnace comprising a vertical heating chamber, a horizontal preheating and cooling chamber, and means for conveying ware in vertically disposed lanes through said pre-heating and cooling chamber.

70 4. An enameling furnace comprising a heating chamber, a preheating chamber, a continuous conveyor means, means for effectuating said conveyor means to move in a substantially vertical direction in said heating chamber, means disposed above said heating chamber for supporting said conveyor means, and means for effecting said conveyor means to move in a horizontal direction in said pre-heating chamber.

75 5. A furnace comprising a vertical heating chamber, a horizontal preheating and cooling chamber, a conveyor means for conveying ware in opposite directions through said chambers wherein burned and unburned ware 80 pass in close proximity in said horizontal chamber.

85 6. An enameling furnace comprising a vertical heating chamber, heating means intermediate the ends of said chamber, a horizontal preheating and cooling chamber, and conveyor means for conveying ware in opposite directions in said chambers.

90 7. An enameling furnace comprising a vertical heating chamber, a horizontal preheating and cooling chamber, a conveyor means for conveying ware in opposite directions in said chamber, said conveyor means adapted to convey burned ware beneath the unburned 95 ware.

100 8. In a furnace a vertical heating chamber having a closed top, a conveyor means for conveying ware in said chamber, a supporting means for said conveyor, said supporting means comprising oppositely disposed stub shafts having sprockets disposed on the inner ends of said stub shafts.

105 9. In a furnace, a vertical heating chamber having a closed top, conveyor means for conveying ware in opposite directions in said chamber, a supporting means for said conveyor, said supporting means comprising oppositely disposed stub shafts having sprockets disposed on the inner ends of said stub shafts, said supporting means disposed exterior of said heating chamber.

110 10. In a furnace the combination of a vertical heating chamber, a preheating and cooling chamber, means for conveying ware through said chambers, said heating chamber comprising a base, a vertical muffle supported by said base and a dead wall space disposed between the top of said muffle and the roof of said heating chamber.

115 120 11. In a furnace the combination of a vertical heating chamber having a closed top, a preheating and cooling chamber, means for conveying ware through said chambers; said heating chamber comprising a base, a vertical muffle supported by said base, and oppositely 125 130

disposed ports in said base, one of said ports adapted to admit ware from said preheating and cooling chamber to said heating chamber.

- 5 12. In a furnace, a vertical heating chamber having a closed top, conveyor means for conveying ware in said chamber, supporting means for said conveyor means, said supporting means comprising oppositely disposed shafts, sprockets disposed on said shafts, and means for securing said shafts against movement upon the reverse movement of said sprockets.
- 10 13. In a furnace the combination of a vertical heating chamber, a horizontal preheating and cooling chamber, conveyor means adapted to move ware in said chamber, and means disposed in said preheating and cooling chamber adapted to restrict any horizontal movement of gas therethrough.

- 15 14. In an enameling furnace, a vertical burning chamber having a sealed top thereon, stub shafts supported exterior of said chamber, conveyor means adapted to support ware through said heating chamber, said conveyor means adapted to pass out of said chamber and engage said shafts while maintaining the ware supported thereby within said burning chamber.
- 20 15. In an enameling furnace, a vertical burning chamber having a sealed top thereon, conveyor supporting means exterior of said burning chamber, conveyor means adapted to support ware within said burning chamber in vertical moving lanes, said conveyor means adapted to pass out of said chamber and engage said conveyor supporting means while maintaining the ware supported thereby within said burning chamber.

- 25 16. In an enameling furnace, a vertical burning chamber having a sealed top thereon, slots in said top, conveyor means adapted to support ware within said chamber, conveyor supporting means exterior of said top, said supporting means adapted to cooperate with said slots to receive said conveyor means as it passes out of said burning chamber, and means on said conveyor means for maintaining the ware carried thereby within the burning chamber.

- 30 17. In an enameling furnace, a vertical burning chamber having a sealed top, slots in said top, conveyor means adapted to support ware within said chamber, adjustable conveyor supporting means exterior of said top, sprockets on said supporting means, said conveyor means adapted to pass out of said burning chamber and engage said sprockets while maintaining the ware supported thereby within said burning chamber.

- 35 18. In a furnace having a heating chamber the combination of conveyor means for conveying ware through said chamber in substantially vertically disposed lanes and sup-

porting means for said conveyor means whereby said conveyor means may pass out of said heating chamber while maintaining the ware within the chamber.

- 40 19. In a furnace the combination of a vertical heating chamber, a pre-heating and cooling chamber associated therewith, means for conveying ware through said chambers, and conveyor supporting means whereby said conveyor means may pass out of said heating chamber while maintaining the ware within the heating chamber.

- 45 20. In a furnace the combination of a vertical heating chamber, heating means disposed intermediate the ends of said chamber, a horizontal pre-heating and cooling chamber, conveyor means for conveying ware through said chambers, and means disposed in said pre-heating and cooling chamber adapted to restrict the horizontal movement of gas therethrough.

- 50 21. In a furnace, the combination of a vertical heating chamber, a pre-heating and cooling chamber, and means for conveying ware through said chambers, said heating chamber having a dead wall space at its top.

- 55 22. In an enameling furnace, a vertical burning chamber, conveyor supporting means disposed exteriorly of and above said burning chamber, conveyor means adapted to support ware within said burning chamber, said conveyor means adapted to pass out of said chamber and engage said conveyor supporting means while maintaining the ware supported thereby within said burning chamber.

- 60 23. In an enameling furnace, a vertical heating chamber, said heating chamber including a vertical muffle supported on a base and a dead wall space disposed between the top of the muffle and the top of said heating chamber, conveyor supporting means disposed above said heating chamber and conveyor means adapted to support ware within said heating chamber, said conveyor means adapted to pass out of said heating chamber and engage said conveyor supporting means while maintaining the ware supported thereby within said heating chamber.

- 65 24. In an enameling furnace, a vertical burning chamber, conveyor means adapted to convey ware through said burning chamber in substantially vertical lanes, means for supporting said conveyor means whereby the ware entering the heating chamber travels upwardly and the ware leaving said heating chamber travels downwardly, means for controlling the heat applied to the ware during its upward travel and independent means for controlling the heat applied to the ware during its downward travel.

- 70 25. In a furnace of the type described, a vertical heating chamber, means for conveying ware through said heating chamber in substantially vertical lanes whereby the

ware moves upwardly in one of said lanes and downwardly in the other of said lanes and means for applying heat to said heating chamber whereby the temperature of the upward lane may be varied from that of the downward lane.

26. In an enameling furnace, a vertical burning chamber, conveyor means supported exteriorly of said chamber and adapted to 10 convey work in substantially vertical lanes through said burning chamber, means for heating said burning chamber and means for controlling the temperature of the opposite sides of said burning chamber whereby the 15 temperature of the ware may be raised to the desired point during its upward travel and maintained at the desired point during its downward travel.

In testimony whereof I hereunto affix my
20 signature this 1st day of December, 1930.

CHAUNCEY ARNOLD DUTTON.
